SHOE DISPLAY DEVICE

William J. De Witt, Auburn, N. Y., assignor to
 Shoe Form Co., Inc., Auburn, N. Y., a corpora-
 tion of New York

Application January 14, 1933, Serial No. 651,774

3 Claims. (Cl. 12—128.1)

This invention relates to an improvement in a shoe display device, and more particularly to means for so treating the shoe that it will present a pleasing appearance when on display in a show case or window or on a counter or shelf.

The primary object of this invention is to provide a cap to close the top opening of the shoe and means for positioning such cap; such positioning means being, for example, a shoe form by which the toe of the shoe is plumped out so that the shoe simulates its appearance when worn on the foot.

Other objects will appear from a consideration of the following description of one embodiment of the invention and of the drawing which forms a part thereof and in which

Fig. 1 is a side elevation of a shoe provided with a cap to close the top opening and embodying this invention, portions of the shoe and the cap being broken away to disclose the invention more clearly;

Fig. 2 is a side elevation, on a larger scale, of the cap shown in Fig. 1;

Fig. 3 is a bottom plan view of such cap; and

Fig. 4 is a sectional view taken along the line 4—4 of Fig. 2.

The shoe 10 selected for the purpose of demonstrating this invention is of the oxford type having a top opening 11 closed by a cap 12. The cap 12 is of celluloid or other resilient formable material having a flange 13 which enters the shoe and bears against the walls thereof and a knob or button 14 which may be removably secured at the center of the top of the cap. The surface of the top is preferably arcuate, as shown in Fig. 2, being higher at the forward end than at the rearward end. The inclination of the flange varies, being greater at the forward portion which engages the vamp of the shoe than at the rearward portion which engages the heel.

Inserted into the toe of the shoe is a shoe form comprising a toe portion 15 and a rearwardly extending back part wire 16 which rests normally against the heel counter. The cap is here shown to be supported in position by means of the shoe form, the forward portion of the flange 13 being inserted between the vamp of the shoe and the cone of the toe portion 15 and the end of the back part wire entering the angle formed at the junction of the top and the rearward portion of the flange 13. The back part wire 16 here shown is looped and the strands thereof bear against the sides of the flange 13. Thus the flange 13 of the cap is yieldably held

against the walls of the shoe at a number of points to resist any tendency of the cap to move downwardly through the top opening into the shoe.

When the cap is to be applied to a shoe having a shoe form therein the forward portion of the flange 13 is inserted between the cone of the toe portion 15 and the vamp of the shoe, the tip of the back part wire is raised and inserted into the cap and then the rearward portion of the cap is slipped down through the top opening into contact with the heel of the shoe.

While one embodiment of the invention has been shown and described, I am not limited thereto since other embodiments may be made without departing from the spirit and scope of the invention as set forth in the following claims.

I claim:

1. Means for providing a pleasing finish to a shoe comprising a shoe form having a toe portion for plumping out the toe of the shoe and a back part wire normally adapted to engage the heel counter of the shoe and hold the toe portion in the plumping out position, and a cap to close the top opening of the shoe, said cap being independent of but supported by the shoe form and held by the back part wire in contact with the heel counter of the shoe.

2. Means for providing a pleasing finish to a shoe comprising a shoe form having a toe portion for plumping out the toe of the shoe and a back part wire normally adapted to engage the heel counter of the shoe and hold the toe portion in the plumping out position, and a flanged cap to close the top opening of the shoe, said cap being independent of but supported by the shoe form, the cap being held in contact with the shoe upper by the top portion of the form and with the heel counter of the shoe by the back part wire, both the toe portion and the back part wire bearing against the inner face of the cap flange.

3. Means for providing a pleasing finish to a shoe comprising a shoe form having a toe portion for plumping out the toe of the shoe and a back part wire normally adapted to engage the heel counter of the shoe and hold the toe portion in the plumping out position, and a flanged cap to close the top opening of the shoe, said cap being independent of but supported by the shoe form, the back part wire entering the cap and bearing against inner face of the cap flange whereby the flange is held against the heel counter of the shoe.

WILLIAM J. DE WITT.
